UNITED STATES PATENT OFFICE

164,096

MOLDED SHOE SOLE

Norman E. Bovay, Naugatuck, Conn., assignor to
United States Rubber Company, New York,
N. Y., a corporation of New Jersey

Application May 21, 1951, Serial No. 15,256

Term of patent 14 years

(Cl. D7—5)

To all whom it may concern:

Be it known that I, Norman E. Bovay, a citizen of the United States, residing at Naugatuck, in the county of New Haven and State of Connecticut, have invented a new, original, and ornamental Design for Molded Shoe Sole, of which the following is a specification, reference being had to the accompanying drawing, forming part thereof.

Fig. 1 is a bottom plan view of a molded shoe sole, showing my new design; and

Fig. 2 is a longitudinal sectional view of the same taken on line 2—2 of Fig. 1.

I claim:

The ornamental design for a molded shoe sole, as shown.

NORMAN E. BOVAY.
